JOHN M. ALLEN, OF TORONTO, ONTARIO, CANADA, ASSIGNOR TO SCOTT & WILLIAMS,
INCORPORATED, OF NEW YORK, N. Y.

HOSIERY AND METHOD OF MAKING SAME

Application filed February 25, 1928. Serial No. 257,021.

The principal objects of the invention are, to provide a stocking with a foot shaped to the contour of the foot of the wearer with the widest part of the toe arranged at the widest 5 part of the foot of the wearer and with the seam which closes the toe located on the bottom of the stocking forward of the rear ends of the gores lying between the top and bottom of the toe, thereby presenting a stocking of 10 exceptionally neat appearance which will be exceptionally comfortable to wear.

A further important object is to devise a structure which will enable the carrying of the instep yarn well into the toe portion. 15 The principal features of the invention consist in the novel formation of the toe of the stocking by lengthening the gore to extend from the widest part of the foot of the wearer and widening a portion of the toe by knitting 20 a gusset into the gore of a lesser length than said gore, the bottom of the toe being formed in two sections joined by looping at a point intermediate of the length of the toe the looping being continued back to the ends of the 25 gore to complete the joining of the top and bottom toe sections.

In the drawings, Figure 1 is an elevational view showing my improved hose as fitted on the foot.

Figure 2 is a side view of the knitted foot shown flat.

Figure 3 is a detail side perspective view of the toe portion showing the manner in which the fabric is knitted prior to looping 35 the two bottom sections of the toe.

Figure 4 is a diagrammatic view illustrating the arrangement of needles on a circular knitting machine adapted to knit the new stocking.

The stocking is shown and described herein knitted upon a circular knitting machine and the heel and body portion of the foot is formed in the usual manner.

When the portion A has been completed to 45 the point B which corresponds with the widest part of the foot of the wearer, the needles knitting the top half are progressively reduced in number to knit a tapered structure.

The instep yarn is continued into the top 50 toe section C for a number of courses, ap-

proximately from fifteen to twenty as may be found desirable and a yarn change is then made to a reinforced yarn and the knitting of the top section is continued, progressively withdrawing needles from action and tapering the structure to the minimum number of stitches between a—a.

When the top section has been completed to the minimum number of stitches which is considerably less than the number usually formed in a stocking, a portion of the needles that have been removed from action in the knitting of the tapering toe section are returned into action to knit a course of stitches F around the end of the toe and to the tapering sides thereof back to the points E which are preferably where the yarn change was made.

A plurality of courses G are then knitted to the course F to form a gusset and in the knitting of this gusset the number of needles in operation is progressively decreased to form the tapered ends H to the gusset.

The needles returned into action to knit the gusset courses are then withdrawn back to the points a—a illustrated in Figure 4 and the knitting of the toe pocket is continued in the formation of the widening toe bottom portion J, the number of needles in action being increased progressively until the needles between the points E—E have been brought into action.

The needles which knit the bottom half of the foot are then brought into action to form the tapered section D of the bottom half and the needles in action are progressively decreased until the number of needles in action between c—c Figure 4 corresponds with the number of needles between E—E used in completing the last course of the bottom section J of the toe pocket.

When the stocking has been knitted thus far the entire complement of needles are thrown into operation and a plurality of looping courses K are knitted to the finished edges; 95 that is, along the edge j of the toe tip J, the tapered edge c of the top toe section, the corresponding tapered edge d of the bottom toe section D and the end edge d' of the section D. The looping courses are then cast on to 100

a looper and the looping L is then completed, joining the tapered extension of the instep, course for course, to the section D of the toe bottom between the points B, which is the end 5 of the foot section and E which is the end of the gusset, and connecting the adjacent ends of the bottom to sections D and J.

The stocking when thus completed has the maximum width discontinued at the widest 10 part of the foot of the wearer and from the points B the stocking continues in a long tapering toe which fits the contour of the foot.

The joining of the toe sections along the gore lines, that is joining d to the line running 15 from the points B to E, and joining the meeting ends d' and j of the bottom toe sections D and J, carries the loop stitching L forward so that it will pass under the foot between the ball portion and the toes so that the bearing 20 portion of the foot will not be in contact with the looping.

In the knitting of a stocking in this manner it will be readily understood that the instep yarn may be continued into the tapering 25 toe section any desirable distance, the length of the continuation being only limited by the length of the gusset required in the widening of the narrow end of the toe.

In carrying the instep yarn into the tapering toe section, that is, past the commencement 30 ends B of the gore, a two fold result is obtained. The instep yarn is knitted in a comparatively tight stitch and the bottom section D of the toe extending beyond the 35 commencement of the gore, being of a heavy or reinforced yarn is a much looser and larger stitch, consequently a stated number of courses in the bottom section is of much greater length in the structure of the stocking than is the corresponding section of the 40 same number of courses of the top. In the looping of these sections together they are connected course for course, consequently the bottom portion is considerably longer than 45 the top which is very desirable as the length of the bottom of the human foot is much greater than the top.

Another desirable feature is the fact of carrying the instep yarn well into the toe 50 end of the stocking so that the reinforcing yarn will not be seen even with a low vamp shoe.

A stocking constructed as described is very 55 desirable. It fits the foot remarkably well without wrinkles: it is comfortable to wear and has a very excellent appearance.

The gusset feature herein shown and described is claimed herein only in connection 60 with the two bottom segments in the toe. The gusset broadly considered also forms subject matter of my copending application Ser. No. 203,000 filed July 2, 1927. The gusset also forms a feature of my application Ser. No. 65 212,527, filed August 12, 1927, and of my ap-

plication Ser. No. 344,192, filed March 5, 1929.

What I claim as my invention is:

1. A stocking having a toe portion comprised of a tapered bottom segment, a tapered top segment and a widened bottom segment integral with said top segment, in combination with looping joining the free tapered edges of the tapered top and bottom segments and joining the meeting ends of the bottom segments. 70

2. A stocking having a toe portion comprising a tapered top segment and a tapered bottom segment each knitted integrally with the foot section, the tapered top segment extending farther toward the toe tip than the tapered bottom segment and having a widened bottom segment integral with the top toe segment in combination with means joining the tapered edges of the tapered bottom and top segments and joining the ends of the two bottom segments. 80

3. A stocking having the top of the toe portion tapered from the end of the foot section and having a gusset knit around the end of the toe and to a portion of the tapered edges thereof and a bottom toe section knitted to said gusset, and a bottom portion of the toe tapered from the end of the foot section and meeting the toe bottom section knitted to the gusset, in combination with looping joining the meeting edges of the bottom sections and joining the outside edges of the top toe tapered section to the corresponding outside edges of the bottom toe tapered section. 90

4. A stocking having a toe portion formed of top and bottom tapered sections extending integrally from the foot, the top section having the instep yarn continued thereinto and having an end portion of a reinforced yarn, a gusset between the top and bottom sections of the toe portion and a partial toe bottom knit integrally therewith, the tapered extension of the toe bottom being formed of reinforced yarn, the courses of the instep 100 yarn of the tapered toe top being looped to the courses of the reinforced yarn of the tapered toe bottom extending from the foot bottom and the end of the tapered bottom toe portion being looped to the partial toe bottom 110 knit integrally with the top. 115

5. A method of making a stocking consisting in first knitting the foot section, then continuing the top half thereof to form a tapered toe top, then knitting a widening toe section to the end of the toe top, continuing the bottom half of the foot to form a tapering toe bottom section of a less number of courses than the tapered toe top, then joining the end of the widening portion of the toe to the end of the tapering toe bottom section and joining the tapering edges of the toe top and tapering toe bottom section to the commencement ends of the taper. 120

6. A method of making a stocking consist- 125

ing in first forming the foot with a fine instep yarn, then continuing the knitting of the instep yarn to form part of a tapering top toe section, making a yarn change in the knitting of the top toe section and continuing knitting of the tapering toe top, then knitting to the tapering toe top a gusset of lesser length than the tapered edges of the toe top, then knitting a widening toe portion to said gusset, and continuing the knitting of the foot bottom with a reinforced yarn to form a tapering bottom toe section and finally looping the end of the widening toe portion to the end of the tapered toe bottom section and continuing the looping to join the courses of the instep yarn of the tapering toe top to the courses of the reinforced yarn of the tapering toe bottom.

7. A method of knitting a stocking consisting in first knitting the foot portion, continuing the knitting of the instep yarn to form part of a tapering toe top, changing yarn, finishing the toe top and continuing with the formation of a widening segment toe bottom, continuing the knitting of the foot bottom to form a tapering bottom toe segment thereon, knitting looping courses around said widening and tapering bottom toe segments and the instep yarn portion of the toe top and looping the looping courses together.

8. A stocking having a tapered toe structure with tapered top and bottom sections, the top of the foot being knit integrally with the toe top, part of the tapered bottom of the toe being knit integrally with the toe top and another part knit integrally with the foot bottom, the latter part being looped to the toe top and to the part of the toe bottom knit with the top.

9. A stocking having a narrowed and widened toe pocket and looping around the bottom of the toe pocket on a line intermediate the point and rear end of the toe, in combination with an extension of said looping in the gores between the top and bottom of the toe and extending from said intermediate line of looping to the rear end of the toe.

10. A stocking having a toe portion comprising a knitted tapered top section and two tapered bottom sections, formed with gore lines extending lengthwise of the foot, a gusset arranged between said sections having its courses extending around the toe point and ending at a line intermediate the point and rear end of the toe, and loop stitching joining the top and bottom sections along the gore lines from the end of the foot portion to the ends of the gusset and joining the adjacent end of the two bottom toe sections.

JOHN M. ALLEN.
